UNITED STATES PATENT OFFICE

HARLOW H. HATHAWAY, OF LOS ANGELES, CALIFORNIA

BURGLARPROOF KEY LOCK

Application filed January 21, 1928. Serial No. 248,328.

My invention relates to key locks whereby a key may be prevented from being turned after the door has been locked so that said key may not be turned by the insertion in the key hole of an implement for this purpose, the key remaining within the lock at all times after said key has engaged the tumblers of the lock, until the key lock has been disengaged it being possible to turn said key at all 10 times when the key lock has been disengaged with said key.

It accordingly is an object of my invention to provide a novel form of burglar proof key lock in which a key hole engaging member of 15 preferred construction is positioned at all times upon the shank of the key, said key being provided with means, such as holes, serrations or the like, with which a key engaging device, movably associated with said member, is adapted to be engaged, so that said key, when said key engaging device is 20 disengaged will be permitted to be turned freely within said member but when said device is engaged with said key the latter will be 25 prevented from being turned.

It is also within the province of my invention to provide a key engaging member which is adapted to prevent any key of any character, whatever from being turned, additional 30 members or devices being provided which are equipped with means adapted to be engaged by a locking means, said members thus functioning to prevent the key from turning.

The above and further objects and advantages of my invention, as will hereinafter more fully appear, I attain by the device constructed in accordance with the description and illustration on the drawings forming a part of my application.

Reference is had to the accompanying drawings, in which similar reference characters denotes similar parts.

In the drawings,

Fig. 1 is a side elevational view of one 45 form of my invention applied to a key,

Fig. 2 is a cross-sectional view, taken on the line 2—2, Fig. 1, looking in the direction of the arrows, but showing the key engaging means disengaged from the key and thus permitting the turning thereof,

Fig. 3 is a similar view showing the key engaging means in engagement with the key, and thus preventing the key from being turned,

Fig. 4 is a view similar to Fig. 1 but showing a modified form of key hole engaging member,

Fig. 5 is a cross-sectional view, taken on the line 5—5, Fig. 4, looking in the direction of the arrows, but showing the key locking device disengaged,

Fig. 6 is a similar view, showing the key locking device in engagement with the key,

Fig. 7 is a side elevational view of another modified form of my invention, illustrating a modified key, and a somewhat different key hole engaging member, and key locking device,

Fig. 8 is a cross-sectional view, taken on the line 8—8, Fig. 7, looking in the direction of the arrows, the key engaging means being disengaged,

Fig. 9 is a similar view, showing the key engaging means engaged,

Fig. 10 is a view similar to Fig. 1, but illustrating a still further modified form of my invention,

Fig. 11, is a cross-sectional view, taken on the line 11—11, Fig. 10, showing the key locking device disengaged,

Fig. 12, is a similar view, showing the key locking device engaged,

Fig. 13 is a side elevational view of a still further modified form of my invention,

Fig. 14 is a cross-sectional view taken on the line 14—14, Fig. 13, showing the locking device disengaged,

Fig. 15 is a similar view, showing the locking device engaged, and

Fig. 16 is a fragmentary longitudinal cross-sectional view, taken on the line 16—16, Fig. 13.

Describing my invention more in detail, it is my purpose to provide a key with a key hole engaging means for preventing said key from being turned by the insertion in the keyhole of an implement to turn said key, said invention being adapted to be applied to any key of any character and design.

As seen in Fig. 1 of the drawings, the key

2, which has a round shank 4, is provided with a set of holes, perforations, depressions, serrations or the like 7 for a purpose presently to be described, said key in practice taking 5 any form desired with a flat shank or itself being a flat key of any kind.

Mounted upon the key 4 is a keyhole engaging means or member 6 which in practice may take a number of forms and still remain 10 within the province of my invention, said member having a cylindrical or other shaped portion 8 for surrounding the shank 4 of the key 2, said shape depending upon the configuration of the shank, sufficient clearance 15 between said shank and said portion being provided so that the key may be freely turned therein. The lower part of the member 6 is preferably flattened and of such a width that it may conveniently be inserted within 20 the keyhole of the lock.

The key 2, together with the member 6, is inserted in the key hole of the lock, it being possible at all times to turn the key in the lock, and in the member 6, until said member is locked to the key in the manner presently to be described.

The member 6 may be formed from a single piece of sheet material, by stamping, cutting, or in any manner desired, and shaped in the 20 preferred form, it being within the province of my invention to manufacture the same to suit the practical needs or contingencies. The lower portion of the member 6 may be crimped or corrugated, as shown at 10, for 35 strengthening the same, or said portion may be flat and held close together, or secured together, either without an intervening spacing device as hereinafter more fully described.

40 The means for locking or detachably securing or engaging the member 6 with the key 2 may be any in practice preferred, and I have shown a number of modifications to this end.

In the form shown in Figs. 1, 2 and 3, a device 12 for engaging the member 6 is shown. 45 This device may be pivoted to, slidable with, or fixed in respect to the key hole engaging member 6, said device having associated therewith in any preferred way a means for engaging the perforations, depressions, holes or serrations 7, so that the key will be locked against any movement.

In said figures the device 12 is slidable vertically, and is corrugated as at 14 to fit the corrugations 10 of the member 6, thus preventing an endwise movement, a key engaging element 16, associated in any preferred way with the device 12, being adapted to enter the holes 7, thus preventing the key from movement. Depending upon the particular means 55 7, the part 16 may be a pin, prong or any element desired. The friction of the sides 14 holds device 12 in either operative or inoperative position.

60 In operation, the key 2 is inserted within

the keyhole with the member 6 engaging the latter, the device 16, as shown in Fig. 2, being out of engagement with the holes 7. In this condition, the key may be turned freely for locking and unlocking the door. To make 70 the key burglar proof the key is turned with the shank in the position shown in Fig. 3, and the device 16 pushed home within the holes 7, the member 6 being thus locked within the keyhole, effectively preventing any turning 75 of said key within the lock by the insertion of an implement from the outside of the door.

In Figs. 4, 5 and 6, I have shown another form of my invention in which the member 6' is formed with a hinge portion 9', a top member 8' being crimped over or otherwise associated with the upper curved parts of the member 6', a spring device 12' provided with a projection 16' being associated in any preferred manner with said member and arranged to be pressed into holes provided in the key shank and penetrating the member 8', which latter as shown is substantially a cylindrical spring. The operation of this form of my invention is identical with that previously described, Fig. 5 showing the key unlocked, and Fig. 6 in locked condition.

80 Figs. 7, 8 and 9 show another modified form of my invention in which the key 2'' has its shank 4'' modified with a thickened part 95 provided with a groove along which the member 6'' is adapted to be slid, the upper portion 8'' of which is equipped with a crimped part 5'' perforated as shown in Fig. 9, for the reception of the pin 16'', secured to the vertically slidable element 12'', a spacer 11'' being positioned between the lower parts of the member 6'', and riveted or otherwise secured thereto. The operation 100 of this form is the same as heretofore described, and hence need not be repeated.

105 Figs. 10, 11 and 12 show a still further modified form of my invention with the same operation, the only changes being the shape of the member 6''' and the serrations or cut out portions 7''' of the key.

In Figs. 13-16 inclusive a key is shown, provided with half round perforated pieces 17''' slidable but non-rotatable thereon.

110 The member 6''' is crimped about the half round pieces, which are provided with holes for engagement by pin 16''' mounted on a vertically slidable element 12''' which embraces the member 6''. The key with its half round pieces 17''' is free to be turned within the member 6''' when the parts are in the position shown in Fig. 14, but when the parts are in the position shown in Fig. 15, that is, with the pin 16''' engaged in the holes of the half round pieces, the key is rotatable 125 with the member 6''' united to it.

120 While I have thus described my invention with great particularity, it will be clear that the same may be modified throughout a wide range. I accordingly do not desire to be 130

limited to the exact details of construction shown and described, but reserve the right in practice to make any and all modifications thereof that fall within the scope of the appended claims.

5 I claim as my invention:

1. In a key lock, a key, a set of key engaging members within which said key is adapted to be moved, a key hole engaging device 10 surrounding said members and adapted to engage the key hole of a lock, and key locking means on said device for engaging said members to prevent said key from being turned.
- 15 2. In a device of the class described, in combination with a key having perforations extending at an angle to the ward thereof, means engaging the key shank from opposite sides thereof and facedly rotatable there- 20 about, and means on one of said key engaging means to lock both of said key engaging means upon the key by engagement with the perforations thereof.
- 25 3. In a device of the character described, in combination with a key, means engaging the key shank and shaped for insertion in a key hole, means engaging said means to connect said first-named means to the key shank, said last-named means and said key having 30 mutually engaging means for locking said key engaging means upon the key shank, and at an angle to the ward thereof.
- 35 4. In a device of the character described, in combination with a key, a key hole shaped member rotatably engaging the key shank, a yielding means engaging said member to connect same loosely to said shank, and mutually engaging devices on said key and yielding means to lock both said member and 40 yielding means upon said shank and at an angle to the ward thereof.

In testimony whereof I have signed my name to this specification.

HARLOW H. HATHAWAY.
